[57] CLAIM

The ornamental design for a cigarette package, as shown and described.

DESCRIPTION

FIG. 1 is a front perspective view of a closed cigarette package showing my new design;

FIG. 2 is a front perspective view of the cigarette package illustrated in FIG. 1 showing the lid in an open condition;

FIG. 3 is a front perspective view of the cigarette package illustrated in FIG. 2 showing the front panel of matches extending outwardly therefrom.

The bottom, rear and side not shown are plain and unornamented.

Fig. 1.

Fig. 2.

Fig. 3
